(57) **CLAIM**

The ornamental design for a “flat handle for a push pin or magnet,” as shown and described.

DESCRIPTION

FIG. 1 is a top front perspective view of a “flat handle for a push pin or magnet” showing my new design;

FIG. 2 is a front elevational view thereof;

FIG. 3 is a right side elevational view thereof, the left side being the mirror image thereof;

FIG. 4 is a top plan view thereof; and,

FIG. 5 is a bottom plan view thereof.

The material shown in phantom in FIGS. 1, 2, 3 and 5 is for environment only and does not form a part of the design.
